CLAIM

USPC **D14/489**; D14/492

The ornamental design for a display screen or portion thereof with icon, as shown and described.

(58) **Field of Classification Search**

DESCRIPTION

USPC D14/489-495; 715/763, 764, 810, 835,
715/837, 846, 967; D18/24-33; D19/6-8;
D20/11, 22-32
CPC G06F 3/0481; G06F 3/04812; G06F 3/04817
See application file for complete search history.

FIG. 1 is a front view of a display screen or portion thereof with icon showing our new design;
FIG. 2 is a front view of another embodiment of the display screen or portion thereof with icon showing our new design;
FIG. 3 is a front view of another embodiment of the display screen or portion thereof with icon showing our new design; and,

(56) **References Cited**

FIG. 4 is a front view of another embodiment of the display screen or portion thereof with icon showing our new design. The long-dash short-dash broken lines represent the bounds of the claimed design and form no part thereof. The short dash broken lines showing of the text in FIGS. 3-4 are included for the purpose of illustrating portions of the article and form no part of the claimed design.
